UNITED STATES PATENT OFFICE.

HERMAN MAYER, OF PHILADELPHIA, PENNSYLVANIA.

DESIGN FOR AN ELECTRIC-LIGHT REFLECTOR.

Application filed July 3, 1929. Serial No. 31,935. Term of patent 7 years.

To all whom it may concern:

Be it known that I, HERMAN MAYER, a citizen of the United States, residing in the city and county of Philadelphia, State of Pennsylvania, have invented a new, original, and ornamental Design for Electric-Light Reflectors, of which the following is a specification, reference being had to the accompanying drawing, forming part thereof.

Figure 1 is an end elevation of an electric light reflector, showing my new design.

Figure 2 is a front elevation thereof.

Figure 3 is a top plan view of Figure 2.

Figure 4 is a fragmentary view on an enlarged scale showing the external configuration.

Figure 5 is a section on the line 5—5 Figure 4.

I claim:—

The ornamental design for an electric light reflector, as shown.

HERMAN MAYER.
